tion of Ohio

Application February 24, 1950, Serial No. 146,119

4 Claims. (Cl. 312—342)

1

This invention relates to a cabinet for filing, storage, transfer or the like in which anti-friction bearings carry part or all of the weight of the drawer and its contents.

One of the objects of the invention is to provide a simple, sturdy cabinet that will operate freely even though the drawer be heavily loaded, to which end the invention provides anti-friction thrust bearings underlying the drawer on each side of the cabinet but well within the lateral limits of the drawer. Another object is to provide a cabinet of this kind in which there is extensive area contact between the drawer and the thrust bearings forming part of the cabinet. Still another object is to provide means for supporting the rear end of the drawer from above, as by means of tracks and cooperating wheels which likewise are provided with anti-friction elements.

Other objects and advantages of the invention will appear from the following description and from the accompanying drawings, in which Figure 1 is a perspective of a cabinet embodying features of the invention; Figure 2 is a fragmentary detail, on an enlarged scale, of the lower right-hand corner of one of the drawers of the cabinet; Figure 3 is a similar detail, likewise on an enlarged scale, of the lower right-hand corner of one of the compartments of the cabinet; Figure 4 is a similar view bringing together the drawer shown in Figure 2 and the compartment shown in Figure 3 to indicate how they cooperate in the cabinet; Figure 5 is a section on a reduced scale through the forward end of one of the compartments of a wide cabinet similar to the cabinet of Figures 1 to 4 but embodying four anti-friction thrust bearings at such forward end; and Figure 6 is a detail on an enlarged scale showing the construction of one of the uprights at the rear of one of the drawers forming part of the cabinet in either case.

In Figure 1, the illustrated cabinet, designated 1, consists of a metal base section 2 which may be included or omitted, as desired; a metal top section 3 which likewise may be included or omitted, as desired; and one or more intervening metal compartments, of which three, designated 4, 5 and 6, are shown. Compartment 4 is represented as closed by a metal drawer 7 in fully retracted position; middle compartment 5 is shown with the cooperating drawer 8 in open position; while in the case of compartment 6 the drawer is omitted entirely for the purpose of revealing the interior construction and the metal shell 9 which encloses the compartment above, below, on two sides and at the rear.

2

Referring to drawer 8, shown as cooperating with compartment 5, front portion 10a thereof is of conventional construction, as are also rear portion 10b and bottom portion 11, neither of which appears in Figure 1. Between front portion 10a and rear portion 10b are two longitudinally extending side portions one of which, designated 12, is on the near side of the drawer and therefore appears in part in Figure 1. The corresponding side portion on the far side of drawer 8 is identical but of the nature of a mirror image of side portion 12. At the base of near side portion 12 is a longitudinally extending reinforcing member 13, which, as seen in vertical cross section, defines a right angle. As indicated in Figure 2, reinforcing member 13 is spot welded to the side and bottom portions of drawer 8 in such fashion that vertically extending part 13a thereof extends upward in intimate contact with the lower part of side portion 12. Horizontally extending part 13b thereof underlies and makes similar contact with the bottom portion 11 of drawer 8. This provides a rigid corner construction for the drawer and, as will appear, permits horizontally extending part 13b to serve as a runner that is coextensive with drawer 8 from front to rear thereof.

Drawer 8 is cut away in conventional fashion as at 14 in such manner that between front portion 10a and rear portion 10b of the drawer side portion 12 thereof for the most part extends upward to only about half of the overall height of the drawer. At the extreme rear and on each of the two opposite sides thereof, a metal upright 15 is spot welded to the inside surface of drawer 8, the upright on the near side of the drawer being indicated by dotted lines in Figure 1 and taking the form shown in full lines in Figure 6. Such upright, which parallels side portion 12 and therefore forms with rear portion 10b of the drawer a vertically extending right dihedral angle, has near its upper end an offset portion 16 on the outer or near face of which is mounted a wheel 17 provided with anti-friction elements; e. g., ball or roller bearings, which elements are adapted to rotate about a common horizontal axis A—A. Wheel 17 is mounted on a horizontal threaded stud 18 which passes through an opening (not shown) in offset portion 16 of upright 15 and to the threaded end portion of which a nut 19 is screwed as indicated in Figure 6, such nut abutting the inner or far face of upper offset portion 16. If desired, spacers (not shown) may be interposed between upper offset portion 16 and either 50 or both of wheel 17 and nut 19.

Toward the top of each compartment are two

metal tracks 21, one on each side thereof, with which wheels 17 cooperate. Such tracks are affixed to shell 9 in the relation indicated in the case of compartment 6 toward the upper left-hand corner of Figure 1. In each instance, track 21 takes the form of an integral channel-shaped member 22 the base of which abuts and is spot welded to the inside of metal shell 9. Upper flange 23 of track 21 is in contact from end to end thereof with the inner upper surface of shell 9 where the latter forms the top of compartment 6. Lower flange 24, which underlies upper flange 23, may be coextensive therewith except that at the forward end thereof it is preferably cut away somewhat, as at 25, to facilitate removal of the drawer from the compartment. As is true also of upper flange 23, lower flange 24 may in the interests of rigidity be doubled back on itself, in which case it will present much the same appearance but will of course be of double thickness. This is particularly desirable in the case of lower flange 24 in view of the fact that wheels 17 ride on it, in consequence whereof it must support a very substantial part of the weight of the drawer.

Like the other compartments, compartment 6 is made up, along with metal shell 9, of a skeleton comprising a metal frame member 26 of which there may, if desired, be more than one but of which there is usually one at least at the forward end of the compartment. Frame member 26 may conveniently comprise a rectangularly-shaped strip-like element extending continuously around the inside of shell 9, the two ends preferably meeting in a butt joint near the middle of the base of compartment 6. Overlying rectangular frame member 26 in the region in which the two ends thereof abut is a metal reinforcing strip 27 of generally similar size and shape but extending only from the far side wall to the near side wall of the compartment. Reinforcing strip 27 is spot welded or otherwise affixed to rectangular frame member 26; the latter is itself fastened, as by spot welding, to metal shell 9.

Near the opposite ends of reinforcing strip 27, circular openings are drilled through the assembly comprising reinforcing strip 27, frame member 26 and shell 9. At the upper end, each of such openings is counterbored to provide an annular shoulder 29 in reinforcing strip 27. A thrust bearing 30 of suitable shape is positioned in each such opening, being held in place therein by a press fit. Such thrust bearing is preferably of the nature of an anti-friction bearing, such as a ball or roller bearing, that is so mounted that the elements thereof rotate about a common vertical axis B—B. As indicated in Figure 4 of the drawings, such axis is within the lateral limits not only of the compartment but also of the cooperating drawer; the reason for this disposition of bearings 30 is so that they can cooperate with runners 13b on the bottom of the drawer and facilitate movement of the drawer into and out of retracted position, this notwithstanding the fact that they carry a substantial part of the load imposed by the drawer and its contents.

As indicated in Figure 3, each bearing 30 consists of a laterally flanged outer race 31 the flange 31a of which is received in and corresponds in height and shape to the counterbore forming shoulder 29a; a laterally flanged rotatable inner race 32 the flange 32a of which extends similarly to the flange 31a forming part of outer race 31, but unlike the latter, extends upward to a point somewhat above the level of rein-

forcing strip 27; a series of anti-friction elements 33 held in place for rotation about vertical axis B—B between outer race 31 and inner race 32; and, underlying anti-friction elements 33 at the unflanged lower end of inner race 32, a retaining ring 34 which is fixed to and rotates with inner race 32. At their flanged upper ends, the two races present the appearance of an externally stepped hollow cylinder, the stepped aspect resulting from the fact that flange 32a does and flange 31a does not extend above the level of reinforcing strip 27; at their unflanged lower ends, the two races appear as spaced hollow cylinders between which are to be seen anti-friction elements 33 and retaining ring 34, the latter in close association with inner race 32.

Bearings 30 extend through frame member 26 to the lower side thereof, preferably being flush with shell 9 as indicated in Figures 3 and 4; this fact, together with the fact that the bearings are relatively shallow, keeps lost space within the compartment at a minimum.

As shown in Figure 4, horizontally extending portion 13b of reinforcing member 13 makes contact with and in fact rides after the fashion of a runner upon flange 32a of inner race 32. Such contact is area contact extending over a substantial part, up to as much as one-half, of the top surface of flange 32a. Thus the downward forces are distributed over a large part of inner race 32, precluding the possibility of extensive deformation of the bottom of the drawer under the weight of its contents. Preferably, but not necessarily, the outer edge of flange 32a is rounded somewhat so as to minimize the likelihood of deleterious frictional engagement between a rough or sharp edge on flange 32a and the lower face of horizontally extending portion 13b of reinforcing member 13. With this arrangement, it is possible to pull or push the drawer out of or into closed position with relatively little effort, friction at the forward end of the compartment being minimized by the presence of thrust bearings 30 and friction at the rear end of the drawer being held to a minimum by the presence of the anti-friction bearings forming part of wheels 17 at the upper ends of uprights 15.

Figure 5 illustrates how it is possible to adapt the invention to a wide compartment; for example, a compartment having a width of 36". In such case, it is simply necessary to incorporate additional thrust bearings 30 in frame member 26 and reinforcing member 27 at one or more places between the thrust bearings near the opposite ends of reinforcing strip 27, at the same time fastening to the bottom portion of the overlying drawer a corresponding number of flat strips 40 adapted to coat with such additional thrust bearings after the fashion of the horizontally extending parts 13b of reinforcing members 13. In the arrangement shown in Figure 5, two strips 40 are shown, the corresponding thrust bearings being located in juxtaposition to them but inwardly of them in the sense that the thrust bearings are offset laterally toward the longitudinal central axis of the bottom of the compartment. In the interest of distributing the weight of the drawer as uniformly as may be practicable, the thrust bearings are preferably spaced equally lengthwise of frame member 26 and reinforcing member 27.

It is apparent that although these constructions, representing preferred embodiments of the invention, provide important advantages, some

of these same advantages may be realized by further modifications of the constructions illustrated in the drawings. Thus it is possible, for example, to dispense with uprights 15 and tracks 21 and, instead, to provide a series of thrust bearings similar to bearings 30 at regular intervals lengthwise of the compartment, each in approximately the same location relative to the side walls of the compartment as the thrust bearings at the forward end thereof. By doing so, the weight of the drawer and its contents, rather than being carried in part by uprights 15, will be carried entirely by two or more series of thrust bearings. Although the preferred material is metal, particularly a ferrous metal such as steel lending itself to spot welding, it is apparent that other materials, particularly wood, may be used for many of the major parts of the cabinet.

It is intended that the patent shall cover, by 20 summarization in the appended claims, whatever features of patentable novelty reside in the invention.

I claim:

1. A cabinet including a frame; a plurality of 25 walls supported by said frame; a drawer movable into and out of a retracted position within said walls; a plurality of thrust bearing assemblies, mounted in openings in a horizontally extending portion of the frame underlying said 30 drawer; each of said assemblies consisting of a

stationary outer race, a horizontally rotatable inner race, and anti-friction means between said inner and outer races; each of said inner races having its upper face raised above said horizontally extending portion of the frame for eccentric surface contact with the bottom of said drawer.

2. A cabinet as in claim 1 in which each bearing assembly is held by a press fit in a corresponding opening in the frame.

10 3. A cabinet as in claim 1 in which there are two bearing assemblies at the forward end of the compartment, one toward the left-hand side and one toward the right-hand side of the frame.

15 4. A cabinet as in claim 1 in which there are more than two bearing assemblies at the forward end of the compartment.
